Primary Examiner — Kathleen L Jones*Assistant Examiner* — Jasmine L. Comedy(74) *Attorney, Agent, or Firm* — Bereskin & Parr LLP/S.E.N.C.R.L., s.r.l.(57) **CLAIM**

The ornamental design for a reef block, as shown and described.

DESCRIPTION

FIG. 1 is a perspective view of a reef block according to the first embodiment;
FIG. 2 is a top view thereof;
FIG. 3 is a bottom view thereof;
FIG. 4 is a front view thereof;
FIG. 5 is a back view thereof;
FIG. 6 is a first side view thereof;
FIG. 7 is a second side view thereof;
FIG. 8 is a perspective view of a reef block according to the second embodiment;
FIG. 9 is a top view thereof;
FIG. 10 is a bottom view thereof;
FIG. 11 is a front view thereof;
FIG. 12 is a back view thereof;
FIG. 13 is a first side view thereof; and,
FIG. 14 is a second side view thereof.
The broken lines in FIGS. 8 to 14 illustrate portions of the reef block that form no part of the claimed design.

1 Claim, 8 Drawing Sheets(56)
